Attorney

UNITED STATES PATENT OFFICE.

WILLIAM H. MCKISSICK, OF TULSA, OKLAHOMA.

SAFETY SHEAVE BLOCK.

Application filed May 3, 1926. Serial No. 106,374.

This invention relates to new and useful improvements in safety sheave blocks.

The object of the invention is to provide a block with removable side guard members, whereby the cable lines are enclosed and the fingers of the workman are protected, but at the same time said block may be easily opened for the removal or insertion of cable lines.

10 A further object of the invention is to provide a block housing having open sides and upright guard plates removably mounted in said open sides in a simple and efficient manner.

15 Another object of the invention is to provide spacer members co-acting with flanges at the upper ends of the guard members to separate the lines of cable and to prevent the hands of the workman being drawn into the 20 top of the block.

A construction designed to carry out the invention will be hereinafter described together with other features of the invention.

The invention will be more readily understood from a reading of the following specification and by reference to the accompanying drawings, in which an example of the invention is shown and wherein:

Fig. 1 is a perspective view of a block constructed in accordance with my invention,

Fig. 2 is an elevation of one of the guard plates,

Fig. 3 is a detail of the lower becket,

Fig. 4 is a horizontal cross-sectional view, 35 and

Fig. 5 is a transverse vertical sectional view.

In the drawings the numeral 10 designates a central vertical partition plate from which 40 upright side bars 11 are spaced by spacer members or blocks 12. Side or cover plates 13 are fastened to the outer ends of the blocks against the side bars and to which they may also be secured. The parts 10, 11, 12 and 13, 45 form a housing through the upper end of which a becket bolt 14 passes. The ears of an upper becket 15 are pivoted on the said bolt on each side of the plate 10.

A lower becket bolt 16 passes through the 50 lower end of the housing and a lower becket is pivoted thereon. This becket comprises a hook member 17 and a keeper member 20, the latter having spaced ears 19 at its lower end receiving an ear 18 on the end of the bill of the hook member. A locking bolt 21 is 55 passed through the ears. When it is desired

to thread the lower becket the bolt 21 is withdrawn and the keeper member 20 is swung to one side as is shown in the dotted lines in Figure 3.

The important feature of the invention resides in guard plates 22 covering the open sides of the housing. Each plate 22 has its lower end rolled to form an integral sleeve 23. A bolt 24 extending through the plates 60 13 also passes through the sleeve and is fastened by a nut 25. The bolt is located at the lower end of the side edges of said plates. The plates 13 are beveled at their upper and lower ends to form inclined shoulders 65 extending to said side edges.

Each plate 22 has laterally extending lugs 70 26 at its upper end engaging in notches 27 in the upper shoulders of the plates 13. The bolts 24 and the notches 27 are set inward 75 from the edges of the plates 13 and this positions the guard plates 22 between the plates 13.

At the upper end of each plate 22 an inclined flange 28 is bent inwardly along the 80 shoulders and directed toward the partition plate 10, leaving only enough space for the lines of cable to pass on each side of the blocks 12. An axle 29 extends through the center of the housing and sheaves 30 are 85 journaled thereon on each side of the partition plate 10 within the housing and below the flanges 28 and blocks 12.

When it is desired to insert or remove cable lines from the housing, the guard 90 plates may be readily removed upon withdrawal of bolts 24. When the plates 22 are in place, the sides of the housing are completely closed and a safe block is had.

Various changes in the size and shape of 95 the different parts, as well as modifications and alterations, may be made within the scope of the appended claims.

What I claim, is:

1. In a safety sheave block, a block housing having a sheave therein and comprising side plates having notches at their upper ends, vertical guards having lugs at their upper ends engaging in said notches, sleeves on the lower ends of the guards, and bolts 100 mounted on the plates and passing through said sleeves, the guards being disposed between the plates.

2. In a safety sheave block, a block housing having a sheave therein and comprising side plates having notches at their upper ends, vertical guards having lugs at their 105 110 115 upper ends engaging in said notches, sleeves on the lower ends of the guards, and bolts mounted on the plates and passing through said sleeves, the guards being disposed between the plates.

upper ends engaging in said notches, sleeves on the lower ends of the guards, and bolts mounted on the plates and passing through said sleeves, the guards being disposed between the plates, spacing blocks between the upper ends of the plates, and inclined flanges on the upper ends of the guards directed toward the blocks.

3. In a safety sheave block, a plurality of 10 upright supports, a becket attached to the upper ends of said supports, side plates attached to said upright supports and covering the same, a sheave journaled between the supports and the side plates, and upright 15 guard plates removably mounted between the vertical edges of the side plates, whereby said guard plates are shielded and protected by the side plates, the guard plates covering

the cable line on both sides of the sheave.

4. In a safety sheave block, a plurality of 20 upright supports, a becket from which said supports are suspended, side plates attached to the outer sides of the supports and extending to each side of said supports, spacer blocks disposed between the upper ends of 25 the side plates and relatively on each side of the becket, vertical guard plates removably mounted along the vertical edges of the side plates and each guard plate having an inturned flange at its top entirely spaced 30 from the spacer blocks, and a sheave journaled between the supports and the side plates.

In testimony whereof I affix my signature.

WILLIAM H. McKISSICK.
